UNITED STATES PATENT OFFICE

REINHARDT DAAE, OF YOUNGSTOWN, OHIO

POKER FOR GAS PRODUCERS

Application filed December 7, 1923. Serial No. 679,140.

The present invention relates broadly to pokers and operating mechanism therefore, and more particularly to a poker for use in gas producers and to improved means for operating the poker to obtain different operating results at different times.

As disclosed in my Patent No. 1,445,300 of February 13, 1923, and as claimed in my Patent No. 1,521,281 of December 30, 1924, I have heretofore proposed the provision of a poker for gas producers with means for mechanically raising the poker and thereafter permitting it to descend under the influence of its own weight. Also I have heretofore proposed, as disclosed therein, to provide in a single poker-operating mechanism, operating means of such nature that if desired the poker could have different characteristic movements imparted thereto. The present invention relates particularly to improved means for mounting a poker, whereby it may be permitted to rest upon a fuel bed and move over the surface for distributing the fuel, if such an operation is desired, or may be adapted to be intermittently raised and lowered in a novel manner where it is deemed advisable to actually poke the fuel bed and break through the upper surface thereof.

In the accompanying drawings, there are shown for purposes of illustration only certain preferred embodiments of the present invention, it being understood that these drawings do not define the limits of my invention, as changes in the construction disclosed therein and in the operation of the producer may be made without departing from the spirit of my invention or the scope of my broader claims.

In the drawings:

Figure 1 is a top plan view partly broken away and partly in section illustrating one form of gas producer equipped with a poker-operating mechanism constructed in accordance with the present invention;

Figure 2 is a vertical sectional view on the line II—II of Figure 1, looking in the direction of the arrows;

Figure 3 is a vertical sectional view on the line III—III of Figure 1, looking in the direction of the arrows;

Figure 4 is a detail transverse sectional view on an enlarged scale through a portion of the poker, this view illustrating a part of the poker-operating mechanism;

Figure 5 is a vertical sectional view on the line V—V of Figure 4, looking in the direction of the arrows; and

Figure 6 is a detail horizontal sectional view illustrating a modified form of poker-operating mechanism.

In the art to which this invention relates, it is desirable at different times to provide means effective solely for the purpose of leveling the fuel bed within the body of the gas producer and serving to distribute uniformly over such fuel bed the coal supplied thereto. At other times, it is necessary, in order to secure proper combustion within the producer and permit the release of the gases, to actually poke or break through the upper layer to the fuel bed. This poking action serves to effectively fill up any cracks which have formed in the fuel bed during the operation of the producer.

In the illustrated embodiment of my invention, there is provided a gas producer 2, which may be of any usual construction. This producer carries at its upper portion a casting 3, which is preferably substantially U-shaped in cross section, to provide a channel 4, for the reception of water to be used for sealing the cover 5 of the producer. This cover is provided with a downwardly projecting flange 6, extending into the channel 4 and below the level of the water therein, whereby the interior of the producer is sealed, as required.

The cover is preferably formed with a machined outer portion 7, adapted to cooperate with antifriction rollers 8, carried on suitable spindles projecting outwardly from the producer body. Also for holding the cover in its proper operative position, there may be provided a second series of rollers 9, having their axes substantially normal to the axes of the rollers 8.

The gas producer illustrated in the accompanying drawings is preferably of the character in which there is a relative rotational movement between the body of the producer

and the cover. In the particular form illustrated, this relative movement is obtained by rotating the cover while maintaining the body stationary, but it will be apparent that the same results might be obtained by rotating the body and maintaining the cover stationary. For producing this rotation of the cover, there is indicated at one side of the producer a motor 10, having a gear 11, on its armature shaft, meshing with a gear 12 on an upper shaft 13, journaled in a housing 14, operatively supported in the desired relation to the cover 5. This shaft, in turn, carries a gear 15, meshing with a gear 15^a on a second shaft 16 extending through the housing. Mounted on the shaft 16 within the housing is a worm 17, in operative engagement with a worm wheel 18, suitably secured to a vertically extending shaft 19. Intermediate its ends, the shaft 19 carries a pinion 20, which meshes with teeth 21, formed on the peripheral portion of the cover 5.

It will be apparent that with the construction described, there is provided a unit driving mechanism which may be bodily removed or placed in position as desired.

Extending transversely of the cover is a shaft 22, having at one end a bevel gear 23, extending downwardly through an opening 36 in the cover of the producer and meshing with an annular gear 24, suitably secured to one edge of the casting 3. With this construction, relative rotation between the body of the producer and the cover is effective for transmitting rotation to the shaft 22. This rotation is, in turn, effective through a gear 24, which meshes with a similar gear 25, for transmitting rotation to the shaft 26. This shaft carries at its opposite end a loosely mounted gear 27, meshing at all times with a gear 28, on one end of a short shaft 29. At its opposite end the shaft 29 is intergeared with a similar shaft 30, whereby the shafts 29 and 30 will be simultaneously rotated in opposite directions at the same speed.

The shafts 29 and 30 are preferably journaled in a suitable casting 31, projecting upwardly from the cover of the producer and having extending vertically therethrough an opening 32 for the passage of the shank 33 of a poker. This shank, at least its upper portion, is preferably substantially rectangular in cross section, to provide opposed faces 34, adapted to be engaged by frictional driving means 35. This driving means, as clearly indicated in Figure 5, may conveniently comprise similar drums carried by the intermediate portions of the shafts 29 and 30, respectively, and having diametrically opposed portions 36 cut away, whereby during the rotation of the drums, the high portions 37 thereof will first come into contact with the sides of the poker shank, and thereafter, the high points will pass out of engagement

and permit the poker to drop under the influence of gravity.

Due to the construction of the driving mechanism, this drop of the poker does not influence the rotation of any of the driving mechanism, and it will therefore be apparent that the movement of the poker in the downward direction is nearly a true gravity drop. The continued rotation of the shafts 29 and 30 in the proper direction, as determined by the relative movement of the cover and body of the producer, will again bring the friction surfaces into operative lifting engagement with the shank of the poker whereby it will again be raised. This operation may be continued as long as desired for intermittently raising and lowering the poker, to tamp or poke the fuel bed.

For guiding the poker accurately during the actuation thereof, there may be provided webs 38, projecting from diametrically opposite sides of the shank and adapted to engage guideways 40 in the casting 31. This prevents any possibility of twisting of the poker during the operation of the producer.

In order to accurately control the frictional engagement between the operating mechanism and the poker, each of the shafts 29 and 30 may be carried at its opposite ends in blocks 41, slidably mounted in suitable ways in the casting 31, and normally urged inwardly toward each other by compression springs 42, cooperating at their outer ends with cross heads 43, and at their inner ends with the blocks 41. By varying the position of the cross heads 43, the compression of the springs may be correspondingly varied and the frictional lifting engagement changed as desired.

At its lower end, the shank 33 carries a poker 44, which may be substantially of the construction set forth in my Patent No. 1,521,281, dated December 30th, 1924. In this construction, the fuel-engaging face of the poker is provided with fuel-distributing channels 45, as clearly shown in Figure 2, and the body of the poker increased in width from the inner end to the outer end thereof, as indicated in Figure 1. In this manner, a substantially uniform tamping action on the entire area of the fuel bed is effected, as the poker acts generally in a radial direction and the increase in width from end to end thereof takes care of the increase in the circumference from the inner to the outer portion of the fuel bed. At times, it may be desired to have the body 44 of the poker simply rest upon the fuel bed for leveling the same and distributing the fuel as supplied to the producer. In order that this operation may take place, the gear 27 has provided on one of its faces a portion 46' of a clutch adapted to cooperate with a similarly shaped portion 46, which is splined to the shaft 26 and adapted to rotate at all times therewith. The clutch portion 46 is movable inwardly into engagement, or out-

wardly to destroy such engagement, with the gear 27, by means of an operating lever 47. This lever may be constructed to cooperate with a bracket 48, having openings 49 therein, adapted to successively register with the opening 50 in the lever as it is moved to its different positions, whereby a locking pin may be passed through the registering openings and hold the lever in either desired position. With the clutch disengaged, it will be understood that the poker rests on the fuel bed for performing the operation set forth.

It is desirable, whether the poker is being operated to tamp the fuel bed or to distribute the fuel, to provide means for determining the character of its action. For this purpose, the poker shank at its upper end, as clearly shown in Figure 3, carries a bracket 51, from which a pivotally mounted rod 52 extends upwardly into a housing 53. This housing is operatively supported, as shown in Figure 1, between spaced channels 54. At an intermediate portion, these channels are pivotally mounted on a bracket 55, extending upwardly from the cover, whereby a rocking movement of the channels is permitted. At one end, the channels carry a counterweight 56, while at the other end they carry a head 57, cooperating with curved arms 58. Both the head 57 and the arms 58 are provided with openings adapted to be brought into registration to receive a locking pin 59, whereby the channels 54 may be positively held in any desired position. As clearly shown in Figure 3, the bracket 48 for the clutch lever 47 may be formed as an integral part of the curved arms 58.

Mounted within the housing 53 in position to surround the rod 52 is a comparatively heavy compression spring 60, the degree of compression of which may be adjustably varied by the nut 61, and follower 62. With this construction, with the counterbalance channels 54 secured in any position, the amount of penetration of the poker into the body of the fuel bed will be determined by the setting of the spring. This may be varied to increase or decrease the extent of the penetrating movement of the poker. On the other hand, when it is desired to have the poker act as a distributing means, the counterbalance arms 54 will be freed by withdrawing the pin 59, whereby the entire body of the poker is substantially counterbalanced and it serves to distribute and level the fuel bed, without exerting any substantial packing action thereon.

In Figure 6 of the drawings, I have indicated a slightly modified form of my invention, in which for the purpose of increasing the frictional lifting engagement between the drums and the shank of the poker, the drums and the faces of the poker shank are provided with cooperating grooves, serrations, or the like 63.

The mechanism for feeding fuel to the producer body may be of any desired construction, having preferably a positively operated fuel-feeding means, such as a drum 64, provided with pockets 65 and delivered through a suitable opening to a distributing bell 66. The specific manner of feeding, however, constitutes no part of the present invention.

The advantages of the present invention arise from the provision of a poker-operating mechanism by means of which the poker may be lifted at will and permitted to drop to penetrate the body of the fuel bed an amount which may be adjustably regulated.

Still further advantages of the invention arise from the construction and mounting of the poker, whereby it may be effectively used as a distributing means for the supplied fuel, without exerting any detrimental packing of the fuel bed.

I claim:

1. In a gas producer of the character described, a fuel bed engaging element, counterbalancing means cooperating therewith for partially carrying the weight of said element, means for moving the element relatively to and independently of said counterbalancing means, and a shock absorbing connection between said element and said counterbalancing means, substantially as described.

2. In a gas producer of the character described, a cover adapted to carry a fuel engaging member, a fuel bed engaging member on said cover and extending therethrough, counterbalancing means supported solely on said cover for said fuel engaging member, a spring shock absorbing connection between the fuel engaging member and said means, and means for holding said counterbalancing means in different adjusted positions, substantially as described.

3. The combination of a poker having fuel engaging and distributing means, means for raising said poker intermittently independently of the fuel level with which it cooperates, counterbalancing means for said poker, connecting means between said counterbalancing means and poker for permitting the poker to distribute fuel while operating independently of said counterbalancing means, and resilient means for limiting the descent of said poker, substantially as described.

4. In a gas producer, mechanism comprising a poker having a vertically-extending shank, means rotatable about an axis at substantially right angles to the axis of said shank, and intermittently movable into and out of frictional engagement with the shank for raising the poker and permitting it to fall respectively, and operating mechanism for said means, substantially as described.

5. In a gas producer, mechanism comprising a poker, means having an irregular surface adapted to be rotated adjacent said poker whereby portions of said surface intermit-

tently frictionally engage the poker to raise the same, and to be rotated out of engagement thereof to permit the poker to fall by gravity, and operating mechanism for said means, substantially as described.

- 5 6. In a gas producer, poker-operating mechanism, comprising a poker, means having an irregular surface adapted to be rotated adjacent said poker whereby portions of said 10 surface intermittently frictionally engage the poker to raise the same, and out of engagement therewith to permit the poker to fall by gravity, and operating mechanism for said means, said means being resiliently urged toward said poker, substantially as described.
- 15 7. In a gas producer, mechanism comprising a poker, means adapted to intermittently move into direct lateral engagement with said poker to raise the same, and then move entirely out of engagement with the poker to permit the same to fall by gravity, operating mechanism for said means, and means for rendering said operating mechanism inoperative, substantially as described.
- 20 23 In testimony whereof I have hereunto set my hand.

REINHARDT DAAE.
